UNITED STATES PATENT OFFICE.

HARVEY LE GEAR, OF CHICAGO, ILLINOIS.

CLAM-SHELL BUCKET.

1,342,996.

Specification of Letters Patent.

Patented June 8, 1920.

Application filed September 24, 1919. Serial No. 325,878.

To all whom it may concern:

Be it known that I, HARVEY LE GEAR, a citizen of the United States, residing at Chicago, Illinois, have invented certain new and useful Improvements in Clam-Shell Buckets; and I do hereby declare the following to be a full, clear, and exact description of the invention, such as will enable others skilled in the art to which it appertains to make and use the same.

My invention relates to so-called clam shell buckets and aims to provide a construction affording decided advantages over the clam shell buckets now on the market both in simplicity of construction, durability and effectiveness of operation. As one feature, my invention aims to provide a clam shell bucket affording an unusually wide spread and having its closing mechanism so arranged as to expend practically all of its power in scooping the material into the bucket halves while utilizing the weight of the scooped material for maintaining the desired penetration. As another feature, my invention aims to support the bucket jaws so that they will normally swing partly open by gravity, to provide a simple and novel mechanism for entirely and positively opening the bucket, and to provide simple means for limiting the opening spread of the jaws. As a further feature, my invention aims to connect the bucket jaws to each other by pivotally connected arms so disposed as to bring the pivot ends of the arms up alongside of the head of the appliance, thereby permitting such an effective reduction in the height of the appliance that the same can be used in a much smaller head room than the clam shell buckets heretofore available. Furthermore, my invention aims to provide a clam shell bucket which will hold the jaw bottoms rigidly spaced and substantially vertical when the bucket is wide open, so as to insure an effective penetration of the material even when digging in clay or river gravel. Moreover, my invention aims to provide a construction employing relatively few and simple parts while affording a positive action both for the opening and the closing of the bucket; to provide simple means for guiding the mechanism clear of the sides of hatchways, to provide means for stiffening both the bucket jaws and the shafts which carry the sheaves for the closing line; and to provide a bucket having its center of

gravity so low that it will not tip easily if used on a slope. Still further objects will appear from the following specification and from the accompanying drawings in which—

Figure 1 is a side elevation of a desirable embodiment of my invention, showing the bucket wide open, and with a part of the head cut away to disclose the arrangement of the closing line.

Fig. 2 is a plan view of the same.

Fig. 3 is a side view of the bucket when closed, drawn on a reduced scale.

Fig. 4 is a similar end view.

Fig. 5 is a fragmentary interior view of the left hand end of the head of the bucket, showing the position of the parts when the bucket is closed.

In the embodiment of the drawings, the appliance of my invention includes a head made of a pair of steel plates 1 suitably spaced from each other so as to allow for the pivoting of the bucket-tilting links between the same. Each of these links is here shown as pivoted near one end of the head on a bolt 3 and as including at its upper portion an arm 4 extending from the head toward the bucket and integral with an inner arm 5 which affords the connection to the opening or holding line 6. For the purposes of this connection, I desirably pivot a pair of sheaves 7 between the head plates 1 and use these sheaves as guides for flexible elements 8 connecting the ends of the inner arms 5 with the closing line 6.

Rigidly secured to each of the outer lever arms 4 so as to coöperate with the latter in forming one of the jaw-tilting links are two straps 28 which diverge downwardly and are pivoted at their lower ends to brackets 9 fastened to the bucket jaws. The two bucket jaws are connected to each other by pivot arms 10 arranged in pairs and each fast upon one of the bucket jaws, the arms comprising each pair being connected by a pivot bolt 11, and the two pairs of arms being spaced from each other transversely of the buckets by a distance greater than the width of the head of the appliance. These arms 10 desirably are so disposed with respect to the bucket halves that their opposed edges aline substantially with the opposed edges of the bucket sides when the bucket is closed, and each arm desirably has an outwardly directed web 18 for the purpose hereafter described. To effect the closing of the bucket,

I mount on each bucket jaw or on the arms 10 carried by the same a shaft 13 carrying sheaves 19 over which the closing line 14 passes after the usual manner of a tackle block construction, this closing line being fast at one end to one of the shafts 11 and being guided by a sheave 15 pivoted to the head of the appliance.

To insure an easy opening of the bucket, 10 I desirably space the pivots for the jaw-tilting links from each other by a distance approximating the distance between the pivotal connections of these links to the bucket jaws when the bucket is closed, so that these 15 links will be approximately vertical when the bucket is closed, as shown in Fig. 3. With the parts thus arranged, the center of gravity of each bucket half will be considerably inward of the head from the pivotal 20 support of the tilting link, so that gravity will partly open the bucket as soon as the strain on the closing line is relaxed. This opening tendency is further increased by the weight of the pivot arms and of the 25 closing mechanism associated with the latter, so that the combined weights will promptly swing the bucket partly open when the strain on the closing line is relaxed. Then since the holding line is connected to 30 the jaw-tilting links through flexible elements 8 and lever arms acting in a direction for swinging these links outwardly, I can speedily open the bucket to any desired extent by a corresponding tension on the holding line. For effective operation, this opening of the bucket is preferably such that the 35 jaw bottoms are substantially vertical as shown in Fig. 1. Consequently, they will readily penetrate material when the bucket 40 is dropped, yet will afford a continuously increasing scooping angle while the bucket halves are being moved toward each other, thereby affording a thrust through the material which increases in horizontal direction as the bucket jaws approach each other 45 and carry an increasing portion of the load. Owing to this increasingly effective angle, I secure a partial filling of the jaws at such an early stage during their closing movement that the weight of the material in the 50 jaws helps to hold these down in the material, thereby insuring a complete filling of the bucket even with such a shallow penetration as can readily be obtained when 55 working in tough materials.

While this scooping or filling of the bucket is occurring, it will be obvious from the drawings that the tackle block arrangement acts in a horizontal direction, so that 60 it is highly efficient in closing the bucket even through clay or other material affording considerable resistance. Furthermore, since these tackle blocks are mounted at a considerable distance from the pivot ends 65 of the arms which connect these bucket

halves, I secure a highly effective leverage while still maintaining the entire operating mechanism above the contents of the bucket. To increase the leverage thus afforded through the pivoting of the arms 10 to each other, I desirably make these arms of such a length that they will extend approximately to the top of the head of the appliance when the bucket is closed, thereby securing the maximum leverage without 70 any increase in head room. To limit the opening of the bucket to the desired extent, I preferably provide coöperative stop formation on the pivot arms substantially at their pivotal connections, as by gripping 75 one of these arms with a lug 16 engaging a corresponding stop 17 on the arm to which it is pivoted. As a simple mounting for the sheaves 19, I desirably provide shafts 13 connecting the laterally opposed arms 10 just above the juncture of these arms with the bucket jaw. Each of these shafts is desirably fast on both of the arms 10 which it connects, and hence rigid with respect to the bucket jaw, so that it prevents a spreading 80 or distorting of the sides of the jaw. I also desirably connect the sheave housing 20 by rigid braces 21 to the pivot brackets at the outer corners of the jaws, as shown in Fig. 2, thereby stiffening both the shaft 13 and 85 the jaw as a whole.

With the appliance thus constructed it will be obvious that with the same length of links and the same height between the buckets and the head, the long pivot arms 100 will swing the bucket jaws to a much wider spread or opening than could be obtained in any construction where the jaws are pivoted to each other close to their forward edges or through arms which have to clear 105 the lower edge of the head. Consequently, I can cover a much larger surface area of material with a bucket of a given size and therefore secure the full contents of the bucket with less penetration of the material, 110 which is important when working in such materials as clay or some kinds of gravel. However, by dropping the bucket when wide open I can secure a deeper penetration when desired, since the scoop bottoms of the 115 jaws are substantially vertical when the bucket is opened wide and since the pivot arms are so arranged as to hold the bucket halves rigidly in this position when the weight of the appliance is carried by the 120 holding line. Then when the strain is being transferred to the closing line, this first operates through the tackle blocks for closing and filling the bucket, and thereafter raises the closed bucket. When the bucket is to be 125 dumped, the gravity action as above explained operates automatically and speedily for this purpose.

Owing to the relatively small height required for my appliance in proportion to its 130

capacity, I can readily operate it in places where head room is limited, as for example in the holds of vessels, and after the bucket has been lowered through the hatchway I 5 can readily open it to a spread much greater than the opening required for clearing it when closed. Furthermore, the sloping webs 18 will readily guide the bucket when it is being raised out of the hatchway, so 10 that I can operate with unusual speed and effectiveness in unloading vessels. By placing the tackle block arrangement directly above the bucket jaws and employing a narrow and light head, I maintain the center 15 of gravity of the appliance rather low even when the bucket is empty and therefore, thus reducing the risk of tipping the bucket over when working on a slope, and I further lower the center of gravity by arranging 20 the pivot arms (as shown in Fig. 1) so that they are far below the head when the bucket is open.

However, while I have illustrated and described my invention in a desirable embodiment, I do not wish to be limited to the details of the construction and arrangement as thus disclosed, it being obvious that the same might be modified in many ways without departing from the spirit of the appended claims.

I claim as my invention:

1. In a clam-shell bucket, a head, a pair of bucket jaws, links pivotally connecting opposite ends of the head with rear portions 35 of the bucket jaws, two pairs of arms fast respectively upon the bucket jaws at opposite sides of the latter and extending substantially along the axis of the appliance and upward alongside the head when the 40 bucket is closed, the arms fastened to each bucket jaw being respectively pivoted to the arms fastened to the other bucket jaw, the pivotal connections between the links and the head being so spaced that the links 45 will be approximately parallel when the bucket is closed.

2. In a clam-shell bucket, a head, a pair of bucket jaws, links pivotally connecting opposite ends of the head with rear portions 50 of the bucket jaws, two pairs of arms fast respectively upon the bucket jaws at opposite sides of the latter and extending substantially along the axis of the appliance when the bucket is closed, the arms fastened 55 to each bucket jaw being respectively pivoted to the arms fastened to the other bucket jaw, and means carried by the head for simultaneously moving the links to open the bucket.

3. In a clam-shell bucket, a head, a pair of bucket jaws, links pivotally connecting opposite ends of the head with rear portions 60 of the bucket jaws, two pairs of arms fast respectively upon the bucket jaws at opposite sides of the latter and extending sub-

stantially along the axis of the appliance when the bucket is closed, the arms fastened to each bucket jaw being respectively pivoted to the arms fastened to the other bucket jaw, lever arms respectively fast upon the 70 links and extending beyond the pivotal connections of the latter with the head, and means operably connected to said lever arms for moving the links about their last named pivotal connections to open the bucket. 75

4. A clam-shell bucket constructed as per claim 3, in which the said means include flexible elements respectively connected to the lever arms, and guides over which the flexible elements operate. 80

5. In a clam-shell bucket, a substantially horizontal head, bucket jaws respectively suspended from the ends of the head, and a pairs of arms fast respectively on the two jaws and pivoted to each other at their free 85 ends, the said arms extending upward substantially along the juncture of the jaws when the bucket is closed and being of such length as to bring their free ends alongside the head when the bucket is closed. 90

6. In a clam shell bucket, a head, a pair of jaws, links pivoted to the head and to the jaws, said links having arms extending at approximately right angles and beyond the pivots thereof, sheaves carried by the 95 head and located below the free inner ends of the arms, cables connected to the said free inner ends of the arms and passing beneath the sheaves in engagement therewith and thence upwardly between the sheaves, 100 and means to close the jaws.

7. In a clam shell bucket, a head, a pair of jaws, links pivoted to the head and to the jaws, said links having arms extending at approximately right angles and beyond the 105 pivots thereof, sheaves carried by the head and located below the free inner ends of the arms, cables connected to the said free inner ends of the arms and passing beneath the sheaves in engagement therewith and thence 110 upwardly between the sheaves, and means to close the jaws including a sheave on each jaw, and a cable secured at one end to one jaw and thence engaged with both of the last named sheaves and passing upwardly 115 between the first named sheaves at points alined with the space between the first-named sheaves.

8. In a clam shell bucket, a head, a pair of jaws, links pivoted to the head and to the 120 jaws and arranged to lie substantially parallel and vertical when the jaws are closed, arms connected to the jaws and to each other, and opening means and closing means for the jaws, said arms being formed and 125 arranged so as to lie substantially parallel to the links and with their inner sides closely adjacent each other when the jaws are closed.

9. In a clam shell bucket, a head, a pair 130

of jaws, links pivoted to the head and to the jaws, said links having rigid arms arranged at an angle thereto and extending toward the center of the head, means to move 5 said arms downwardly to effect opening of the jaws, arms connected to each other and to the jaws, and closing means associated with the last named arms.

10. In a clam shell bucket, a head, a pair of jaws, links pivoted to the head and to the jaws and arranged to lie substantially parallel and vertical when the jaws are closed, arms connected to the jaws and to each other, and opening means and closing 15 means for the jaws, said arms being formed and arranged so as to lie substantially parallel to the links when the jaws are closed.

11. In a clam shell bucket, a head, a pair of jaws, outer means extending vertically 20 between the jaws and head to support the jaws when the latter are closed, means to open the jaws, inner means connected to each other and to the respective jaws to open the latter, said inner means when the jaws 25 are closed lying approximately parallel to the outer means, and means to close the jaws.

12. In a clam shell bucket, a head, a pair of jaws, opening means connected to the

head and jaws, and closing means for the 30 jaws, said closing means having sloping webs extending beyond the opening means to guide the bucket in raising the latter out of a hatchway.

13. In a clam shell bucket, a head, a pair 35 of jaws, opening means connected to the head and jaws, and closing means for the jaws, said closing means having means which project outwardly and are formed to engage a hatchway to thereby guide the 40 bucket when raising the latter out of a hatchway.

14. In a clam shell bucket, a horizontal elongated head, a pair of jaws, links pivoted to the outer ends of the head and to 45 the jaws and arranged to lie substantially vertical when the jaws are closed, means to operate the links, arms pivoted at their inner ends to each other and at their outer ends to the inner ends of the jaws and 50 formed to have their said inner ends lie approximately in the plane of the head and adjacent the center of the length of the head when the jaws are closed, and means to close the jaws.

55
Signed at Chicago, September 20th, 1919.

HARVEY LE GEAR.
